RIBBON VIBRATING MECHANISM FOR
TYPEWRITING MACHINESLaurence B. Hill, Syracuse, N. Y., assignor to
Smith-Corona Inc., Syracuse, N. Y., a corpora-
tion of New York

Application January 19, 1952, Serial No. 267,233

15 Claims. (Cl. 197—157)

1

The invention relates to improvements in ribbon vibrating mechanism for typewriting machines.

The principal object of the invention is to provide means selectively settable to vibrate the inked ribbon of a visible typing typewriter to cover the printing point with a selected one of several zones of the ribbon and also to maintain the ribbon in a normal printing point exposing position for typing stencils.

A further object of the invention is to provide a simple and efficient ribbon vibrating mechanism for accurately controlling the throw of the ribbon for type impact on upper, medial and lower zones of the ribbon.

A further object of the invention is to provide a ribbon vibrating mechanism adjustable to prevent both underthrow and overthrow of the ribbon and striking of the ribbon by the type while the ribbon is in normal rest position, which mechanism also is conveniently accessible for repair and adjustment, consists of few and sturdy parts, and can be manufactured at low cost and be assembled with ease.

A further object of the invention is to provide a ribbon vibrating mechanism which will force a stuck ribbon vibrator from a shifted position to its normal rest position, or at least to a point where the type will strike the newly selected zone of the ribbon, whenever the setting of the vibrating mechanism is changed.

A further object of the invention is to provide a ribbon vibrating mechanism having improved means for positively insuring that the type will not strike the ribbon while the mechanism is set for stencil typing.

A further object of the invention is to provide both an improved guiding means for the ribbon vibrator and an improved operating connection between the guided vibrator and its actuating means.

To the above and other ends which will appear hereinafter, the invention consists of the features of construction, arrangements of parts and combinations of devices hereafter described and particularly pointed out in the appended claims.

In the accompanying drawings:

Fig. 1 is fragmentary side elevational view of a typewriter equipped with a ribbon vibrating mechanism embodying the invention in its preferred form and showing said mechanism set for type impact on the lowermost zone of the ribbon;

Fig. 2 is a fragmentary top plan view of the typewriter with parts broken away to show the improvements;

2

Fig. 3 is a fragmentary detail side elevational view of the typewriter with the vibrating mechanism shown set for type impact on the lowermost zone of the ribbon and with the parts positioned as at the time of type impact on the ribbon;

Fig. 4 is a view similar to Fig. 3, but showing the mechanism in its stencil setting and with the parts positioned as at the time of type impact;

10 Fig. 5 is a detail front elevational view showing the type bar guide, the ribbon vibrator and adjacent parts;

Fig. 6 is a detail sectional view on the line 6—6 of Fig. 5; and

15 Fig. 7 is a detail perspective view showing the setting control knob and adjacent parts.

The improved ribbon vibrating mechanism is shown embodied in a typewriter having a set of manually operable type bar actions for actuating the universal bar of the ribbon vibrating mechanism, the type bars being fulcrumed in known manner on the usual arcuate pivot wire carried by a rearwardly inclined type bar segment which is shiftable downwardly in a rearwardly inclined plane by known means from a normal lower case typing position to a shifted upper case typing position. Only so much of this machine is shown and well be described as is necessary to a clear understanding of the present invention.

20 The machine has a main frame comprising two side plates 10 and 11, a rearwardly inclined cross plate 12, and cross bars 13, 14 and 15. A key lever guide comb 16 is held at its ends to the side plates, and a key lever stop pad 17 is held to the upper portion of the comb by a retaining device 18. The type bar segment 19 is held by suitable means, including two screws 20 (Fig. 5), to a downwardly case shiftable and rearwardly inclined segment carrier or support 21 which is located at the front face of cross plate 12. The type bar guide 22 extends upward above the segment and has its lower portion clamped to the front face of the segment by two screws 23 (Fig. 5) so that said guide shifts with the segment.

25 The platen 24 is carried by the usual carriage (not shown) to reciprocate transversely of the machine. The type bars 25, one of which is shown in Fig. 1, are fulcrumed in the segment on the pivot wire 26 to strike at a printing point on the upper front quadrant of the platen slightly above the upper end of the type guide, as is common in this style of typewriter.

30 The type bars are actuated by individual key actions, each of which actions comprises a key 27, 35 a key lever 28, a bellcrank 29, a link 30, an up-

standing sub-lever 31, a link 32 and a returning spring 33. The key levers support the keys in four banks as is usual, one key lever of each bank being shown in Fig. 2. Each key lever has a pin and slot connection 34 with the forwardly extending arm of its associated bellcrank 29, these connections being staggered from bank to bank, as shown in Fig. 2, for uniform rocking of the bellcranks by the key levers. The bellcranks are all of identical size and shape and are fulcrumed on a pivot rod 35 carried by bar 13. The upstanding sub-levers 31 are of graduated length and are fulcrumed at their lower ends on a pivot rod 36 carried by bar 14. The key levers are fulcrumed on a pivot rod 37 carried by bar 15. The links 32 connect the upper ends of sub-levers 31 with the heels of the type bars. The links 30 connect the upwardly extending arms of the bellcranks with the sub-levers 31 intermediate the ends of the sub-levers. The returning springs 33 are connected to the upwardly extending arms of the bellcranks to restore the type bar actions to normal rest position.

The type bar action system is not claimed per se herein but is disclosed to show one suitable type action system for actuating the improved ribbon vibrating mechanism. It will be obvious to those skilled in the art that other manually or power operated type action systems may be employed. The improved ribbon vibrating mechanism now will be described.

The ribbon vibrator 38 is located as usual midway the sides of the machine, is rectilinearly reciprocable up and down to cover and uncover the printing point, and its upper or head portion is formed with the usual pair of laterally spaced ribbon guides through which the inked ribbon (not shown) is threaded. The head portion of the vibrator is slidably held against the rear face of a forwardly offset upper portion of the type bar guide 22 by two bent guide lugs 39 which are formed on said vibrator portion and slidably embrace the parallel vertical side edges and the front face of said type bar guide portion. Below said guide lugs 39 the vibrator has a narrow lower or stem portion which is provided at its lower end with a pair of laterally projecting guide lugs 40. The lower portion of the type bar guide, which is clamped to the front face of the type bar segment by the screws 23, is formed with a longitudinal channel 41 in its rear face. This channel overlaps the vertical side edges of a narrower slot 42 in the type bar segment. Slot 42 extends downward from the upper chordal edge of the segment midway said edge, and the guide lugs 40 slidably engage the side edges of channel 41 and the opposed faces of the segment and channel. The vibrator is thus guided at different points along its length against fore and aft and side-wise movements to minimize possibility of the vibrator canting, jamming or bending in use.

At a point along its length between, and spaced from, the two pairs of guiding lugs 39-39 and 40-40, the stem portion of the vibrator is provided with a pair of rearwardly extending and laterally spaced ears 43 to which are fixed the ends of a horizontal pin 44 on which there is journaled an anti-friction roller or sleeve 45. The vibrator is reciprocated by a bellcrank which is spring biased to a normal rest position in which said bellcrank supports the vibrator in a normal lowered rest position wherein the upper edge of the ribbon is below the printing point and the type cannot strike the ribbon.

The vibrator reciprocating bellcrank comprises 75

a rock shaft or long axle 46 which extends horizontally across the machine behind the frame plate 12 from the right hand side plate 11 to a point slightly to the left of the longitudinal center line of the machine. This shaft has fixed thereto a forwardly extending rock arm 47 and a pendent rock arm 48. The shaft 46 is journaled at its left hand end on a pivot screw 49 threaded through a bracket 50 secured to frame plate 12, and is journaled at its right hand end on a pivot screw 51 threaded through side plate 11. Bellcrank arm 47 is located medially of the sides of the machine and has a longitudinal slot 52 in its forward end through which passes the pin 44 and the anti-friction roller or sleeve 45. Bellcrank arm 48 is fixed to shaft 46 adjacent the right hand end of said shaft and has a laterally offset lower portion which is located at the outer side of frame plate 11 and is connected with the upper portion of said arm by a horizontal intermediate stop portion 48a of the arm which extends through a clearance aperture 53 in frame plate 11. The lower portion of arm 48 is formed with an edge which curves in a substantially circular arc at the front and lower end edges of said arm portion to provide a rearwardly and downwardly curved cam edge 48b. A horizontal stud 60 projects outward from the lower portion of arm 48 between the stop portion 48a of the arm and said curved edge of the lower portion of the arm.

A return spring 54 is connected to bellcrank arm 48 and to a stop bracket 55 to bias the bellcrank and vibrator to their respective rest positions, which positions are adjustable by adjustment of said bracket. Bracket 55 has an arm extending inward through aperture 53 and carrying a stop 56 abutive by stop portion 48a of arm 48 to arrest spring return of the bellcrank and vibrator. This bracket 55 and stop 56 are adjustable about the axis of the bellcrank, said bracket being journaled on hub 51a of a nut 57 which is threaded on pivot screw 51. The bracket has an arcuate slot 58 concentric with said screw 51 and through which extends a clamping screw 59 which is threaded into frame plate 11 to lock the bracket in adjusted position. The cross plate 12 and segment carrier 21 are provided with clearance notches 12a and 21a, respectively, for the bellcrank arm 47.

The spring-retumed bellcrank 46-47-48 is rockable from its rest position by a spring-retumed actuating mechanism which is drivable from a normal rest position by each of the type bar actions on their printing strokes. Said mechanism is variably settable by a manually operable setting mechanism to lift the vibrator on the printing strokes of the type bars to present any selected one of three different zones of the ribbon for type impact, or to render said actuating mechanism ineffective to rock the bellcrank from rest position. This bellcrank actuating mechanism, its setting mechanism, and certain vibrator overthrow preventing stop means are mounted on the main frame of the machine and now will be described.

The actuating means for the bellcrank 46-47-48 comprises a type action operated universal bar 61, a variably settable actuating link 62 reciprocable by the universal bar, a spring 63 for restoring the bar to rest position, and an adjustable return stop device hereinafter described for the bar. The universal bar 61 is a straight bar which is fixed adjacent its upper edge on a horizontal rock shaft 64 and depends from said shaft with its rear face, adjacent the lower edge

of the bar, normally located closely in front of the upper end portions 29a of the type action bellcranks 29 for forward rocking of the universal bar by the respective bellcranks on the printing strokes of the type actions of which they are a part. The universal bar rock shaft is journaled at its left hand end on a pivot screw 65 threaded through frame plate 10. The rock shaft extends through a notch 11a in frame plate 11 and has a reduced right hand end portion 64a journaled in a bracket 66 which is fixed to plate 11 at the outer side of said plate.

A hub 67, which is adjustable around the rock shaft between plate 11 and a sheet metal bracket 66 and held in adjusted position to the shaft by a set screw 68, is formed with a pendent arm 69 and an upstanding arm 70. Arm 69 carries a horizontal pivot 71 to which the front end of link 62 is connected. The return spring 63 has its rear end connected to link 62 and its front end connected to the lower end of arm 69 below pivot 71. The upstanding arm 70 has fixed to its upper end an outwardly projecting padded stop 72 which normally abuts the rear edge of an upstanding stop finger or lug 73 formed on the sheet metal bracket 66. This finger is bendable fore and aft of the machine to adjust the rest position of the universal bar.

The reciprocable or pitman link 62 is formed of sheet metal and has two longitudinal slots in its rear end portion forming three fingers whose rear end portions are bent inward to provide three bellcrank actuating lugs or fingers 74, 75 and 76 which are stepped seriatim relatively to each other rearward and downward different distances from the link pivot for selective presentation behind the stud 60 on bellcrank arm 48 to pull said arm forwardly on the printing strokes of the type actions.

The above-described actuating mechanism for the ribbon vibrator actuating bellcrank is selectively settable by manually operable means mounted on the main frame of the typewriter. This setting means shifts the pitman link 62 around its pivot 71 to change the setting of the actuating mechanism, and it is releasably detentable in four different positions in which it supports and guides the pitman link to reciprocate longitudinally in any selected one of four different paths. This setting mechanism also serves other purposes hereinafter described.

The operating handle or knob 77 of the setting mechanism is detachably fixed on the forward end of a short handle shaft 78 by a set screw 79 and may be adjusted around said shaft by loosening said screw and turning the knob relatively to the shaft. The shaft extends loosely through an upstanding front cover plate 80 of the typewriter and is journaled in a short bearing sleeve 81, the reduced forward end portion of which has a driving fit in a hole in a main frame part 11b extending inwardly transversely of the machine from the right hand side plate 11.

A short rock arm 82 has a hub portion detachably held to the rear end of the shaft 78 by a set screw 83 and adjustable around said shaft when the screw is loosened. The knob abuts the front face of plate 80 and the rock arm abuts the rear end of sleeve 81 to hold the knob, shaft and rock arm against movement fore and aft of the machine. The connected knob, shaft and rock arm serve as a retaining device for the front cover plate 80. Knob 77 is provided on its front face with a pointer 84 to selectively point to the desired one of the four setting indicating indicia 75 Fig. 3 on the printing stroke of any one of the type

or letters "R," "M," "B" and "S" provided on the front cover plate 80.

A link 85 is connected at its upper end to rock arm 82 and at its lower end to the forward end of a sheet metal lever 86. Lever 86 has a flat mid-portion held against the outer face of a side plate 11 by a shouldered pivot screw 87, and its forward arm is bent to pass through a clearance hole 88 in said side plate and its rear arm is bent to offset the rear portion of said arm from the outer face of said plate. The pitman link extends across the outer face of the offset rear portion of lever 86 and has, adjacent its rear end, a longitudinal guide slot 89 through which extends the shoulder portion of a shouldered horizontal supporting, guiding and retaining screw 90 for said link, which screw is threaded into the lever 86 adjacent the rear end of said lever.

To exactly determine the four set positions of the above described knob-operated setting means, to positively limit the range of movement of said means, and to releasably detent said means in each set position, an adjustable detent device and coactive adjustable stops are provided. This device consists of a vertically adjustable sheet metal rack 91 having four V-shaped notches 92 in its forward edge, a detent lever 93 connected to the rear arm of lever 86 by a horizontal pivot 94, a detent roller 95 journaled on a horizontal pivot 96 at the lower end of a pendent arm of lever 93, and a pull spring 97 connecting an upwardly and forwardly extending arm of lever 93 to the rear arm of lever 86 to snap the roller successively into the notches 92 as lever 86 is rocked. The rack 91 has two forwardly extending stop fingers 98 and 99 respectively abutted by the roller 95 when the roller is fully seated in the uppermost and lowermost ones of the notches 92 to positively arrest shifting of the setting means. The rack 91 is clamped to the outer face of the frame side plate 11 in vertically adjusted position by two clamping screws 100 and 101 which pass through vertical slots in the rack and are threaded into said side plate. Desirably, the lever 86 is provided with a clearance hole 102 to afford convenient access to screw 101 in the "stencil" setting of the setting means.

At its rear end the lever 86 is formed with two longitudinal slots dividing the rear end portion of the lever into three fingers whose rear end portions are bent inward to form three stop lugs 103, 104 and 105 which are stepped seriatim rearward and downward relatively to each other different distances from the lever pivot 87 for selective presentation in front of the rounded lower front edge portion of the rock arm 48 of the ribbon vibrator actuating bellcrank 46-47-48. The upper edges of these stop lugs preferably are beveled rearward and downward for easy coaction with the cam edge 40b of bellcrank arm 48, as hereinafter more fully explained.

In Figs. 1, 2 and 3 the ribbon vibrating mechanism is shown set for vibrating the ribbon to its highest limit of movement for impact of the type on a lowermost longitudinal zone of the ribbon. In this setting, the detent roller 95 is seated in the lowest one of the rack notches 92 and on the lower stop finger 99 on the rack 91, the pointer 84 on knob 77 points to the indicating letter "R" on the front cover plate, the actuating lug 74 on the pitman link 62 is behind and in contact with the stud 60 on arm 48 of the vibrator actuating bellcrank in the rest position of the parts and rocks the bellcrank into the position shown in Fig. 3 on the printing stroke of any one of the type

bar actions, and the three stop lugs 103, 104, and 105 are lowered out of the path of forward movement of arm 48 of the bellcrank. To prevent overthrow of the vibrator in this setting of the ribbon vibrating mechanism it is desirable to provide an overthrow stop which acts as closely to the vibrator as is convenient. To this end a padded overthrow stop 106 is mounted over the bellcrank arm 47 to be engaged by the upper edge of said arm near the pin-and-slot connection 44, 45, 52 to the vibrator, as shown in Fig. 3, substantially as a type bar action completes its printing stroke. Stop 106 is mounted on a bracket 107 secured to the frame cross plate 12.

When knob 77 is turned to register the pointer 84 with the setting indicating letter "M," the actuating lug 75 on the pitman link 62 is positioned behind stud 60 and spaced slightly to the rear of the stud to afford such initial lost motion between said lug and stud that the vibrator is lifted only far enough on the printing strokes of the type bar actions for type impacts on a medial longitudinal zone of the ribbon. In this setting of the mechanism, the overthrow stop lug 103 on lever 86 is, in the rest position of the parts, positioned opposite and spaced forwardly from the rounded lower front edge portion of bellcrank rock arm 48 to be engaged thereby on the printing strokes of the type bar actions to prevent overthrow of the ribbon.

Turning of the knob to register the pointer with the indicating letter "B" positions the actuating lug 76 behind stud 60 and spaced still farther rearward from said stud to afford such initial lost motion between said lug and stud that the vibrator is lifted only far enough on the printing strokes of the type bar actions for type impacts on an uppermost zone of the ribbon. In this setting the overthrow stop lug 104 on lever 86 is positioned in front of and spaced from the rounded lower front edge portion of bellcrank arm 48 to be engaged thereby on the printing strokes of the type bar actions to prevent overthrow of the ribbon.

In the "stencil" setting, shown in Fig. 4, the knob is turned to register the pointer with the indicating letter "S" and the pitman link is entirely inoperable on the stud 60, so that the bellcrank and vibrator remain in rest position during actuation of the type bar actions. In this setting, the detent roller 95 is seated in the uppermost one of the notches 92 in rack 91 and also is engaged under stop finger 98 on said rack. Also in this setting, the stop lug 105 on lever 86 is positioned in front of, and in contact with, the rounded lower front edge portion of bellcrank arm 48, as shown in Fig. 4, to positively hold the bellcrank and vibrator from movement out of rest position.

The stop lugs 103, 104 and 105 on lever 86 will each coat with cam edge portion 48b of bellcrank arm 48 to cam the bellcrank and vibrator back toward rest position in the event of the vibrator being stuck in an elevated position on the type bar guide when a setting change for a shorter ribbon throw is made, and this cam action also prevents a stuck vibrator and bellcrank from blocking a change of setting. In moving from the "R" to the "M" setting with the vibrator stuck in an elevated position on the type guide, the stop 103 will engage cam edge 48b and either dislodge the stuck vibrator for return to rest position by spring 54, or will force the bellcrank and vibrator to its actuated position for typing on the middle ribbon zone, so

that the type will strike the desired part of the ribbon in any event. In shifting to the "B" setting from the "M" setting the stop 104 will act in a similar manner on the cam edge 48b in the event the vibrator is stuck. In shifting into the stencil setting stop 105 always will coat with cam edge 48b, if the vibrator is stuck out of rest position, and will force the vibrator and bellcrank into rest position and positively hold them locked there until the setting is changed. The beveled upper edges of the stop lugs 103, 104 and 105 make the above described cam action easier or smoother.

The spring urged detent roller will coat with the pointed teeth separating the rack notches 92 to complete any setting change if the knob 77 is released before the roller is fully seated in a notch. The pull lugs 74, 75 and 76 and the stop lugs 103, 104 and 105 are bendably adjustable fore and aft of the machine for accurate coaction with stud 60 and arm 48. The various other adjustments previously described make possible extremely accurate control of the ribbon vibrator. The spring-retumed universal bar is always free to return on the return strokes of the type bar actions even if the vibrator should stick in an elevated position on the type bar guide.

I claim:

- 30 1. A typewriting machine having a ribbon vibrating mechanism which comprises a setting handle, a setting lever extending fore and aft of the machine and connected at its forward end with said handle and fulcrumed between its ends for up and down rocking thereof by said handle into different set positions, a spring-retumed universal bar stroked forwardly by type actions of the machine on their printing strokes, a return stop for said bar, a spring-retumed belicrank having forwardly extending and pendent arms and rockable about an axis extending transversely of the machine, a ribbon vibrator pivotally engaged with the forwardly extending arm of the bellcrank and guided for up and down reciprocation thereby, a return stop for said bellcrank, an actuating link extending fore and aft of the machine and having a pivotal connection at its forward end with the universal bar by which it is reciprocable forwardly and backwardly respectively on the type-action-imparted and spring-retumed strokes of the universal bar, said link having also a supporting pin-and-slot connection with said lever by which it is rockable up and down by said lever about said pivotal connection, means for releasably detenting said setting handle and lever in selectively set positions, limit stop means for determining two opposite limit settings of the handle and lever, a plurality of stops carried by the rear end of said lever and stepped progressively rearwardly and downwardly relatively to each other for selective presentation in front of the pendent bellcrank arm to control the extent of movement of the bellcrank from its spring-retumed position, the rear and lowermost of said stops in one of said limit settings of the lever being presented in front of and in contact with said pendent bellcrank arm to lock the bellcrank in returned position, and means carried by said link and pendent bellcrank arm for establishing in each setting of said lever, except said last-mentioned one of said limit settings, a pull connection between said link and arm, each of which pull connections is effective to rock said arm forwardly a different distance.
- 35
- 40
- 45
- 50
- 55
- 60
- 65
- 70

2. A typewriting machine, as claimed in claim 1, wherein the detenting and limit stop means for the setting handle and lever comprise a fixed upstanding rack having a row of notches in one longitudinal edge thereof, one for each set position of the handle and lever, a spring urged detent roller carried by the lever to move up and down along said rack edge and seat in said notches, and two limit stops carried by said rack at opposite ends of said rack edge and respectively engageable by said roller as it seats in different ones of the two endmost notches of said row of notches.

3. A typewriting machine, as claimed in claim 1, wherein the pull connection establishing means comprises a lateral projection on the pendent bellcrank arm, and a plurality of laterally extending projections on said link stepped progressively rearward and downward relatively to each other and selectively presentable behind said projection on said arm to start rocking of said arm at different points in the type-action imparted strokes of the universal bar.

4. A typewriting machine, as claimed in claim 1, wherein said pendent bellcrank arm and each of said stops on the lever have surfaces coactive, during rocking of the lever from one of its limit settings to that in which the bellcrank is locked in returned position, to cam the bellcrank toward its returned position in the event of the vibrator being stuck in elevated position.

5. A typewriting machine having a ribbon vibrating mechanism comprising a spring-returned bellcrank having forwardly extending and pendent arms and rockable about an axis extending transversely of the machine, a ribbon vibrator pivotally engaged with the forwardly extending arm for up and down reciprocation to vibrate the inked ribbon of the machine into and out of type impact receiving position, a spring-returned rockable member located forward of the pendent bellcrank arm and automatically forwardly rockable on the printing strokes of the types of the machine, a lever having an arm which extends rearward toward the pendent bellcrank arm and is manually settable up and down about an axis extending transversely of the machine, a bellcrank actuator having a pivotal connection at its forward end with said member and a fore and aft slidable connection with said lever arm in rear of said pivotal connection, which two connections support the actuator for fore and aft reciprocation and for up and down setting movements about said pivotal connection, means for releasably detenting said lever arm in upper and lower limit settings and in at least one intermediate setting, and a plurality of lateral projections stepped rearward and downward relatively to each other on the actuator and selectively presentable by movement of said lever arm into its respective lower and intermediate settings to exert a forward pull on the pendent bellcrank arm at the same distance from the bellcrank axis on the forward rocking strokes of the spring-returned rockable member.

6. A typewriting machine, as claimed in claim 5, having on said lever arm an abutment which is presented in front of and in contact with said pendent bellcrank arm while said lever arm is in its upper limit setting to prevent movement of the bellcrank from its spring-returned position.

7. A typewriting machine, as claimed in claim 5, in which the detenting means detents the lever arm in two intermediate positions, the actuator has three of said rearwardly and down-

wardly stepped projections, the lever arm has three abutments stepped rearward and downward relatively to each other, the two upper ones of which abutments are selectively presentable in front of the pendent bellcrank arm by the respective intermediate settings of the lever arm to limit forward swinging of said bellcrank arm, and the lowermost one of which abutments is engaged with the front of said bellcrank arm in the upper limit setting of the lever arm, and in which a stop is mounted on the main frame above the forwardly extending arm of the bellcrank for engagement therewith to limit upward movement thereof while the lever arm is in its lower limit setting.

8. A typewriting machine, as claimed in claim 5, having a main frame on which the spring-returned bellcrank, lever, spring-returned member, actuator and detenting means are mounted, the forwardly extending arm of the bellcrank being located medially of the sides of the frame and its pendent arm extending laterally outward through one side of the frame and then downward outside of that side of the frame, the rearwardly extending arm of the lever and also the spring-returned member, actuator and detenting means all being located at the outer side of said one side of the frame, adjustable return stop means for the spring-returned bellcrank, said machine also having adjustable return stop means for the spring-returned member mounted on the frame at the outer side of said one frame side.

9. A typewriting machine having a ribbon vibrating mechanism comprising a ribbon vibrator guided for up and down reciprocation, a bellcrank having forwardly extending and pendent arms and rockable about an axis which extends transversely of the machine, a push-pull connection between the vibrator and the forwardly extending bellcrank arm, a return stop for the bellcrank, a return spring connected to the bellcrank to urge its pendent arm rearward against said return stop to yieldingly hold the vibrator pulled downward to maintain an inked ribbon of the machine below the writing line, spring-returned means which receives forward strokes on the printing strokes of types of the machine, a pivot movable fore and aft of the machine by said means and extending transversely of the machine forward of said pendent bellcrank arm, a pull link extending rearward from and held to said pivot, a return stop for said means and link, a laterally projecting stud on the pendent bellcrank arm, a plurality of pull lugs extending laterally from said link and stepped progressively rearward and downward relatively to each other different distances from said pivot for selective presentation behind said stud to rock the bellcrank different distances from its returned position, and means for releasably detenting said link in different rocked positions around said pivot for longitudinal reciprocation by said pivot, in one of which rocked positions of the link said stud is out of the paths of movement of all of said pull lugs, and in each of the other ones of which positions of the link a different one of said pull lugs is effective on said stud to rock the bellcrank from its returned position.

10. A typewriting machine, as claimed in claim 9, in which said detenting means comprises an upstanding stationary member having a row of notches in one longitudinal edge thereof, a member manually rockable up and down and supporting said link to rock therewith and reciprocate relatively thereto, a two-armed lever pivoted on

11

said rockable member to rock fore and aft of the machine, a detent roller journalled on one arm of the lever to roll along the notched edge of said stationary member when the rockable member is rocked, and a spring connecting the rockable member and the other arm of said lever to yieldingly press said roller to said edge of the stationary member.

11. In a typewriting machine, a type bar supporting segment having an upper edge and a slot extending downward from said edge midway the ends of the segment, an upstanding type bar guide having a type bar and ribbon vibrator guiding upper portion above said segment edge and a lower portion detachably clamped to the front of the segment and overlying said slot, said type bar guide having a longitudinal channel in its rear face wider than and straddling said segment slot, a ribbon vibrator having a ribbon guiding head portion and a pendent stem portion, the head portion of the vibrator having a pair of oppositely disposed guide lugs slidably engaging the longitudinal edges and front face of said upper portion of the type bar guide and slidably holding said head portion of the vibrator to the rear face of the said type bar guide portion, the stem portion of the vibrator having a pair of oppositely disposed and laterally projecting guide lugs at its lower end slidably confined between the segment and type bar guide at opposite sides of said segment slot with their outer ends slidably engaged with the side walls of said channel in the type bar guide, a pair of laterally opposed ears extending rearward through the segment slot from the stem portion of the vibrator intermediate said two pairs of guide lugs, a horizontal pin extending between and secured to said ears, a roller journalled on said pin, a vibrator actuating arm extending forward toward the segment and having in its forward end a longitudinal slot in which said roller is engaged, and means for vibrating said arm up and down respectively on the printing and return strokes of the type bars of the machine.

12. A typewriter having a ribbon vibrating mechanism which comprises a ribbon vibrator, a bellcrank rockable about an axis extending transversely of the machine, said bellcrank having a forwardly extending arm connected to the vibrator to reciprocate it up and down and having also a pendent arm which is formed with laterally offset upper and lower portions and a laterally extending intermediate portion, type action actuating means operable on the lower portion of said pendent bellcrank arm to rock it forwardly on the printing strokes of said actions, a bracket pivotally adjustable about the bellcrank axis, means to hold the bracket selectively adjusted, a return stop on said bracket located behind said

12

intermediate portion of the pendent bellcrank arm, and a return spring connected to said bracket and pendent bellcrank arm and normally holding the intermediate portion of said pendent arm rocked against said stop.

13. In a ribbon vibrating mechanism for a typewriting machine having a ribbon vibrator actuating bellcrank and means for rocking the bellcrank in one direction about its axis on the printing strokes of the types of the machine, the combination of a bracket adjustable about the axis of the bellcrank, a spring connected to the bracket and bellcrank to return the bellcrank to a rest position, and a return stop for the bellcrank held to said bracket in the path of return movement about the bellcrank axis of a part of said bellcrank.

14. In a typewriting machine having an upstanding detachable front casing plate, a main frame having a transversely extending portion abutted by the rear face of said plate, and ribbon vibrating mechanism having a part selectively settable to effect different extents of vibration of the inked ribbon of the machine, the combination of setting means for said part comprising a bearing sleeve extending fore and aft of the machine and having its forward end secured in an aperture in said frame portion, an oscillative shaft extending through said front plate and bearing sleeve, a control knob fixed on the forward end of said shaft and abutting the forward end of said sleeve and the front of said plate, a rock arm detachably fixed on and rotatively adjustable about the rear end of the shaft and abutting the rear end of said sleeve, and means connecting said rock arm and said settable part of the ribbon vibrating mechanism for selectively setting said part.

15. A typewriting machine, as claimed in claim 14, having a spring-urged detent carried by said connecting means, an endwisely adjustable rack on the main frame with which said detent is coactive to releasably maintain each of at least three selected settings of the ribbon vibrating mechanism, two limit stops carried by said rack for engagement by said detent to determine two limit settings of said mechanism, and means on said knob and the front of said plate coactive to indicate the respective settings of said mechanism.

LAURENCE B. HILL.
